SURFACER

Frederick Riebel, Jr., Dewey M. Dow, and Lawrence M. Henson, Toledo, Ohio, assignors to Air-Way Electric Appliance Corporation, Toledo, Ohio, a corporation of Delaware

Application January 25, 1932, Serial No. 588,833

6 Claims. (Cl. 91—39)

Our invention relates to surfacers of the type embodying a renewable cartridge of surfacing material and has for its object to provide an applicator adapted for employing a renewable cartridge comprising a filled collapsible tube adapted to lie parallel to and closely adjacent the surface being treated when the surfacer is in use.

More specifically, it is our object to provide, in a surfacer an applicator and collapsible tube assembly wherein the applicator forms a casing or container for the collapsible tube and may be dissociated from the wax cartridge very easily and quickly.

The present invention embodies particularly a holder, a presser head, a cartridge, and a distributor in the form of a flexible casing preferably of fabric, extended around the cartridge and secured to the head.

A further object is to provide, in such an arrangement, a distributor which, like the cartridge, may be dissociated from the remaining elements of the surfacer for renewal purposes and yet which is adapted to be used over and over again in connection with a number of cartridges, as may be desired.

Another object is to provide such an arrangement wherein the distributor may be dissociated from the head speedily and easily.

Another object is to provide an arrangement wherein the distributor is so formed that it is easy to arrange in it a new cartridge and impossible to incorrectly arrange the cartridge in assembling the device.

Another object is to provide an arrangement wherein the head is adapted for attachment to either of several types of holders.

Our invention further aims to attain the foregoing object in a structure which is of comparatively simple, durable and inexpensive construction.

With these and other objects in view our invention consists in the construction, arrangement, and combination of the various parts thereof, whereby the objects contemplated are attained, as more fully set forth in the accompanying specifications, pointed out in our claims, and illustrated in the accompanying drawings, in which:

Fig. 1 is a plan view of a surfacer embodying our invention.

Fig. 2 is an inverted plan view of the same.

Fig. 3 is a plan view of the surfacer without the holder and head.

Fig. 4 is an end elevation showing the invention

arranged with a vacuum cleaner floor tool acting as the holder.

Fig. 5 is a plan view of the extended distributor.

Fig. 6 is a detail sectional view taken transversely through the waxer, and

Fig. 7 is a detail sectional view taken longitudinally through one end of the surfacer.

The material for which this invention is particularly adapted is semi-fluid wax, and in the following descriptions, this material will be specifically referred to without thereby intending to limit the scope of the invention.

A waxer of this invention embodies generally a wax package "A", a presser head "B", and a holder "C" (see Fig. 6).

The wax package "A" comprises a renewable cartridge 10, a distributor 11, and a back plate 12, the latter forming part of the head "B".

The head "B" comprises the back plate 12, the studs 13 rigidly secured thereto and projecting upwardly, the clamp plate 14 provided with openings 15 receiving the studs 13, and wing nuts 16 threaded upon the studs 13 and serving to draw the back plate 12 and clamp plate 14 toward each other.

The holder "C" in the preferred form shown in Fig. 6, comprises a handle 17, and a claw 18 formed integrally with a ferrule 19 secured upon the end of the handle 17.

The closed ends of the claw 18 are slotted as 30 at 20 to receive the studs 13, and the wing nuts 16 engage the upper face of the claw, securing the same in contact with the upper face of the clamp plate 14.

The distributor 11 is preferably formed of a 35 fairly heavy tough fabric although it may be of any flexible material such as for instance leather or composition, and is faced with a layer of soft absorbent material 21, such as felt or any material suitable for distributing non-liquid wax to 40 a surface to be treated. Openings 22 are provided in the distributor being arranged centrally and longitudinally thereof, and when the waxer is ready for use, the operator simply takes a sharp instrument and punctures the tube in which the 45 wax of the cartridge 10 is contained, in registry with the openings 22.

The arrangement of the openings 22 diagonally as shown provides a wax feeding mouth in a series of openings without unduly weakening the webs of fabric 23 between said openings. This provides for a maximum spreading range together with maximum strength and durability in the distributor.

The distributor is in the form of a rectangular

receptacle, its end portions being turned back and secured to the edge binders 24 as shown in Fig. 5. These end portions form flaps 25 which extend over the ends of the cartridge 10 as shown 5 in Fig. 7.

In Fig. 5, one side of the applicator is shown spread out horizontally while the other side extends vertically toward the eye of the observer. This latter side is provided with buckle elements 10 26 and the former side is provided with co-acting buckle elements 27, both of a conventional well known construction, and both secured to the edge binders 24.

In assembling the package "A", the cartridge 15 10 is first placed within the distributor 11, the ends of the cartridge being slipped under the flaps 25, the back plate 12 is thence arranged above the cartridge the sides of the distributor are folded over the sides of the back plate, and 20 the buckles 26-27 are fastened so as to snugly draw the distributor around the cartridge 10. The use of the particular type of buckle shown makes it possible to adjust the distributor cartridge as the latter becomes smaller during the 25 ejection of its contained wax.

The clamp plate 14 has the side flanges 28 which engage against the edge binders 24, with a certain amount of resiliency so as to exert some tension against the distributor 11, aiding 30 in the adaptation of the distributor to the cartridge as the latter shrinks in size. The bead 29 on the edge of the back plate 12 aids in the securing of this result by tending to hold the distributor away from the back plate 12, the buckles 35 27-28 pulling the edges of the distributor toward each other in a flat plane.

Instead of the holder "C" shown in Fig. 6, the floor tool C' of a conventional type of vacuum cleaner may be employed.

40 Ears 30 are upstruck from the head 14, and yokes 31 are hinged to these ears. The yokes 31 are provided with depressions 32 to receive the semi-spherical heads 33 of an element which is found embodied in each end of the particular 45 floor tool C' illustrated.

The lips 34 of this floor tool engage against the upper surface of the head 14, and the wing nuts 16 may be turned so that their wings are lined with each other and may thence be received within the mouth of the floor tool, between the lips 34.

The head 14 is provided with an upstruck bracket 35 having a shoulder 36 terminating in an upwardly projecting ear 37, the latter being receivable between the lips 34 and the shoulder 36 engaging against the lower edge of the end wall 38 of the floor tool. The particular construction of the head for attachment to the floor tool of a vacuum cleaner is shown more 55 in detail in our co-pending application Serial No. 588,835 and is described here only sufficiently to show the adaptability of this invention to either a handle holder of the type shown in Fig. 6 or a vacuum cleaner.

65 In the operation of the device, the applicator is placed against the floor or other surface to be treated with the distributor facing 21 in contact with such surface, and is then moved back and forth over the surface in a direction transverse to the common axis of the opening 22 and parallel to the vertical plane of the handle 17.

The operator may bear down upon the handle so as to produce varying amounts of pressure for feeding wax through the openings 22. As 70 the wax feeds through the openings, it will be

distributed over the surface by the distributor facing 21.

When the device is used with a vacuum cleaner, the weight of the cleaner itself may be employed for providing the pressure for feeding wax and may be supplemented by manual pressure. 5

It is readily apparent how the distributor, being a separate element, may be renewed.

At the same time, the cartridge is entirely unconnected with the distributor, being simply 10 loosely received therein and it is therefore possible to renew the cartridge without renewing the distributor.

The end flaps 25 form pockets for the reception of the ends of the cartridge, and when the device 15 is assembled, are clamped between the cartridge and the back plate 12. Should a tube or container of thin and frangible material be employed for the wax, the securing of the end flaps 25 in frictional contact with the under side of the 20 back plate will guard against bursting the ends of the cartridge and thus a completely enclosed casing including the distributor and the back plate, will be provided.

It is to be noted that the functions of the binding strips 24 are several. To begin with, they make it easy to handle the distributor when folding it around a cartridge. They transmit the pull of the buckle fasteners to each portion of the fabric material of the distributor uniformly, and 30 provide support for the distributor against the expansive pressure produced in the use of the device, during its entire length.

Another function of the binding strip is to provide a surface against which the clamp plate may 35 engage. This is particularly useful where it is desired to employ the clamp plate as a means for securing the edges of the distributor instead of the buckle fasteners. It is to be understood that these buckle fasteners may be dispensed with if 40 desired and the distributor secured between the clamp plate and the back plate by clamping engagement of the two. The rigid bindings serve as a means for clamping the side portions of the distributor so that there will be no slipping at any 45 point along its edges.

We claim as our invention:

1. In a waxer, a head including a back plate and a clamp plate, a collapsible wax cartridge in contact with the lower face of the back plate, a 50 flexible distributor extending around said cartridge, and holding the same against the back plate, fastening means connecting the extremities of said distributor above the back plate, means connecting the clamp plate and the back plate 55 and urging the clamp plate against the upper surfaces of both said extremities of the distributor, said means comprising threaded studs secured rigidly to the back plate and projecting upwardly through the clamp intermediate said 60 distributor extremities plate and nuts threaded on said studs and a handle secured to the clamp plate by means of said studs.

2. In a waxer, a back plate, a collapsible wax cartridge in contact with the lower face thereof, a 65 flexible distributor extending around said cartridge and holding it against the back plate, the extremities of said distributor being extended over the back plate, and selectively adjustable buckles connecting said extremities of the distributor above the back plate.

3. In a waxer, a back plate, a collapsible wax cartridge in contact with the lower face thereof, a 70 flexible distributor extending around said cartridge and holding it against the back plate, the 75

extremities of said distributor being extended over the back plate, adjustable fastening means connecting said extremities of the distributor above the back plate and adapted to take up slack in said distributor occasioned by a decrease in the volume of the cartridge and a clamp plate detachably secured to the back plate and covering the edges of said distributor and said fastening means.

10 4. In a waxer, a back plate, a collapsible wax cartridge in contact with the lower face thereof, a distributor comprising a substantially rectangular sheet of flexible material provided with end pockets receiving the ends of said cartridge, the side portions of said distributor being extended over the respective side portions of the back plate, and fastening means connecting said side portions above the back plate the terminal portions of said pockets being engaged between the back plate and the cartridge.

15 5. In a waxer, a back plate, a collapsible wax cartridge in contact with the lower face of said back plate, a distributor comprising a substan-

5 tially rectangular sheet of flexible material, rigid bindings on the edges of said distributor, end pockets formed by the end portions of said sheet of material folded back upon themselves and secured by said bindings, and fastening means attached to said bindings and connecting the side portions of the distributor above said back plate.

6. In a waxer, a back plate, a collapsible wax cartridge in contact with the lower face thereof, a flexible distributor extending around said cartridge and holding it against the back plate, the extremities of said distributor being extended over the back plate, adjustable fastening means connecting said extremities of the distributor above the back plate and adapted to take up slack in said distributor occasioned by a decrease in the volume of the cartridge, a clamp plate detachably secured to the back plate and covering the edges of the distributor and said fastening means, and a handle secured to said clamp plate.
